Robert L. Epstein**(57) CLAIM**

The ornamental design for a bottle, substantially as shown and described.

DESCRIPTION

FIG. 1 is a front, top and right side perspective view of a bottle showing our new design;

FIG. 2 is a rear, top and right side perspective view thereof;

FIG. 3 is a rear, bottom and left side perspective view thereof;

FIG. 4 is a front, bottom and left side perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and,

FIG. 10 is a bottom plan view thereof.

The broken lines which appear in the figures depict parts of the bottle that form no part of the claim.
